UNITED STATES PATENT OFFICE.

FREDERICK R. L. STOTT AND ELI E. SHIERK, OF HAMILTON, ONTARIO, CANADA,
ASSIGNORS OF ONE-THIRD TO OSCAR W. HAIST, OF HAMILTON, ONTARIO,
CANADA.

EMERGENCY-BUMPER FOR VEHICLES.

1,355,182.

Specification of Letters Patent.

Patented Oct. 12, 1920.

Application filed July 2, 1920. Serial No. 393,556.

To all whom it may concern:

Be it known that we, FREDERICK R. L. STOTT and ELI E. SHIERK, subjects of the King of Great Britain, residing at Hamilton, in the county of Wentworth and Province of Ontario, Canada, have invented certain new and useful Improvements in Emergency-Bumpers for Vehicles, of which the following is a specification.

10 Our invention relates to improvements in emergency bumpers for vehicles, and more particularly to compressed air controlled bumpers for automobiles, surface cars and the like whereby by means of compressed air 15 a protective bumper or fender may be instantaneously lowered or adjusted to protect and pick up any pedestrians who may accidentally assume a position in the path of an approaching vehicle of the class specified.

20 The invention consists essentially of an elevated casing suitably attached to the forward end of a vehicle and containing an apron rolled upon a roller mounted in said 25 casing and adapted to be unrolled to a position extending from said elevated casing to the ground, air cylinders embodying means for actuating said apron, compressed air tank, air lines, and automatic means for 30 maintenance of the system.

35 The invention has for its object, primarily to provide a device whereby elimination of fatal accidents and casualties caused by collision between vehicle and pedestrian may 40 be reduced to a minimum by the provision of an instantaneous operative mechanism by affording means in the forward part of the vehicle which may be instantaneously lowered in order to pick up or fend any pedestrian who may inadvertently walk in front 45 of the approaching vehicle.

A further object is to provide an appliance of the class described which will be operated more expeditiously than would a 50 hand operated mechanical device.

A still further object is to provide a device of the class described which will be simple, durable, efficient in operation, and comparatively inexpensive to manufacture, 55 at the same time being highly efficient in its purpose.

These, together with other objects, may be attained by the construction, combination and arrangement of the parts as will

hereinafter be more fully described, illustrated in the accompanying drawing and pointed out in the claims hereunto appended.

With reference to the accompanying drawings, Figure 1 is a plan view of the apparatus illustrated in connection with and as 60 may be adapted to an automobile by way of example.

Fig. 2 is a sectional side elevation of Fig. 1, taken on the line 1—1;

Fig. 3 is an enlarged detailed front elevation of the actual bumper or fender;

Fig. 4 is a cross-sectional side elevation of the bumper taken on the line 3—3 in Fig. 3;

Fig. 5 is an enlarged sectional side elevation of the apron operating mechanism;

Fig. 6 is an enlarged detailed angular elevation of one of the parts of the bumper; and,

Fig. 7 is a front elevation of the bumper showing the apron in extended position.

Similar reference characters refer to similar parts throughout the several views.

As heretofore specified, we illustrate our invention as adapted to an automobile, the Figs. 1 and 2 representing generally the 80 chassis of an automobile, the frame thereof being designated by A, the wheels by B, the axles by C, the motor or engine by D, the propeller shaft by E, the steering wheel by F, the steering wheel column by H, the cooling radiator by J, and the springs by M.

The bumper casing, indicated by 2, is supported in an elevated position from the road by substantially horizontal brackets 3, secured to the forward end part of the frame 90 A, as shown in Figs. 2 and 3, and includes angular end parts 2'. This casing comprises top, sides and ends, the bottom being open. Mounted and journaled in the casing is a roller 4 and auxiliary rollers 4', all being 95 connected by knuckle or universal joints 5.

Secured to the roller 4 is an apron 6, preferably constituted of fabric material, and normally rolled thereupon, being retained in said normal position by the spring 100 7, but capable of being extended or unrolled by means hereinafter to be described, to an angular position reaching within a small distance from the ground.

The free end of said apron is attached 105 to a bar 8 hingedly secured to a connecting rod 9, and adapted, when the said apron is in extended position, to assume a position

parallel to the ground by means of the hinges 8'. Rubber or other cushioning and shock absorbing material 10 is secured to the forward part of the bar 8.

5 Aprons 6' similar to the apron 6 are attached and rolled upon the rollers 4'.

Flat end pieces 11, rigid with the rollers 4', are provided for the purpose of applying keys or wrenches adapted to increase or decrease as the case may be, to the tension of the springs 6.

In order to augment the strength of the apron 6, we provide a cord or tape 12 attached to the central portion thereof, and 15 adapted to wind upon a grooved sheave 13 in the corresponding portion of the roller 4.

Rigid with each side member of the frame A of the vehicle are cylinders 14 having 20 slideable therein pistons 15 rigid on one end of the piston rods 16 which pivotally connect with the connecting rods 9 at 18.

The said piston rods are sleeved through stationary cross-heads 17 in the interior of the cylinders, and between the cross-heads 25 and the pistons are inserted spiral push springs 19 adapted to retain the pistons in normal position at dead center in the cylinder heads 20, as shown in Fig. 5.

It will be seen that while the pistons 15 30 are in the above described position, the apron 6 will be wound upon its roller 4, and not extended.

The connecting rods 9 operate through longitudinal slots in the cylinders 14 and 35 stops 21 are provided on said rods and adapted to engage the rear ends of said slots when the pistons 15 have reached their dead centers in the cylinder heads, and consequently prevent said pistons from striking 40 the cylinder end plates 22. 23 are governor rods pivotally connected at 24 to the forward end parts of the cylinders 14, and having pivot and slot connections at 25 to the connecting rods 9 intermediate of their 45 ends. A bucket washer, indicated by 26, is secured to the piston in order to seal compression.

A tank 27, for containing compressed air, is located in a convenient and suitable position in the chassis, and is shown suspended in the rear frame by way of example.

An air line pipe 28 communicates with the cylinder heads 20 and with the tank 27, and another air line pipe 29 communicates with said tank and with an air pump 30 secured to and operated by the engine D.

An automatic check valve 31 in the pipe 29 keeps the air from returning to the pump 30, after the latter has ceased to operate.

60 A two-way valve 32 is inserted in an intermediate position in the pipe 28, and is actuated from the driver's seat by means of a lever 33 rigid with a stem 34 connected to the said valve and rotatable in a bearing 65 secured to the steering column 4.

The operation of the invention is as follows:

While the engine D is in motion, air is pumped to the tank 24 until a pressure amounting to approximately 80 pounds is 70 attained, when the pump 30, which is automatic, ceases to operate.

When the driver of the vehicle notices the probability of a collision with a pedestrian, he opens the valve 32 whereupon the compressed air in the tank instantaneously forces the pistons 15 to the opposite end of the cylinders 14 and consequently actuating the apron-lowering mechanism.

The apron will remain in extended position until the valve 32 is closed whereupon it will rewind upon the roller and the pistons 15 will be returned to normal position by the springs 19.

Having now fully described our invention, what we claim and desire to secure by Letters Patent is:—

1. In a device of the class described, the combination with the frame of a vehicle, of a bumper secured across the front of the vehicle and having rearwardly deflected end parts, a roller journaled in said bumper, short length rollers journaled in the deflected portions of said bumper, universal joints connecting said rollers, aprons secured to said rollers, bottom rods secured to the free ends of the aprons, means for lowering and elevating said bottom rods, and means for re-rolling said aprons simultaneously with the act of elevating said bottom rods.

2. In a device of the class described, the combination with the frame of a vehicle, of a bumper, a roller mounted in the bumper, an apron rolled on said roller, a bottom rod secured to the free end of said apron, cylinders mounted in said frame, pistons operative in said cylinders, means connecting said pistons with said apron and adapted to extend the same from said roller to a point 110 near the ground, means for tensionally retaining said pistons at dead center at the cylinder heads, and means for actuating said pistons.

3. In a device of the class described, the combination with the frame of a vehicle, of a bumper, a roller mounted in the bumper, an apron rolled on said roller, a bottom rod secured to the free end of said apron, cylinders mounted in said frame, pistons operative in said cylinders, connecting rods connecting with said piston and with said bottom rod, means for tensionally retaining said pistons at dead center at the cylinder heads, and means for actuating said pistons.

4. In a device of the class described, the combination with the frame of a vehicle, of a bumper, a roller mounted in the bumper, an apron rolled on said roller, a bottom rod secured to the free end of said apron, cyl-

inders mounted in said frame, pistons operative in said cylinders, connecting rods connecting with said pistons and with said bottom rod, stationary cross-heads in said cylinders, spiral push springs in said cylinders between said cross-heads and said pistons, a pipe communicating with the heads of said cylinders and with a source of compressed air, and a controlling valve in said 10 pipe.

5. In a device of the class described, the combination with the frame of a vehicle, of a bumper, a roller mounted in said bumper, an apron rolled on said roller, a bottom rod 15 secured to the free end of said apron, cylinders mounted in said frame, pistons having piston rods and operative in said cylinders, connecting rods connecting with said piston rods and with said bottom rod, a 20 movement governing arms pivotally connected to members rigid with said cylinders and having pivot and slot connections with said connecting rods, means for tensionally retaining said pistons at dead center at the 25 cylinder heads, a pipe communicating with

said cylinder heads and with a source of compressed air, and a controlling valve in said pipe.

6. In a device of the class described, the combination with the frame of a vehicle, of a bumper, a roller mounted in said bumper, an apron rolled on said roller, a bottom rod 30 secured to the free end of said apron, cylinders mounted in said frame, pistons operative in said cylinders, connecting rods connecting with said pistons and with said bottom rod, means for tensionally retaining said pistons at dead center at the cylinder heads, a compressed air tank mounted in said frame, a pipe communicating with said 35 tank and with said cylinder heads, a control valve in said pipe, and means for constantly retaining and maintaining the air pressure in said tank.

5. In testimony whereof we have affixed our 40 signatures.

FREDERICK R. L. STOTT.
ELI E. SHIERK.

Witness:

H. G. HENDRY.
